ENVELOPE

Charles E. Cather, Worcester, Mass., assignor to
United States Envelope Company, Springfield,
Mass., a corporation of Maine

Application August 8, 1932, Serial No. 627,895

8 Claims. (Cl. 229—71)

The present invention relates to an envelope so constructed as to serve for the transmission, by mail or otherwise, of a card or other inclosure that is appreciably smaller in both dimensions than the area bounded by the envelope's edges,— notwithstanding which disparity of size, and lack of fit between the card and the envelope, the sendee's name and address appearing on said card are maintained in registry with an opening 10 or window in the face of the envelope.

Other and further objects and advantages of the invention will be made apparent in the following detailed description thereof, taken in connection with the accompanying drawings, in 15 which—

Fig. 1 is a plan view of a blank or sheet adapted for manufacture into an envelope embodying my invention.

Fig. 2 is a rear view of the completed envelope 20 made from the blank of Fig. 1, and illustrating the maintenance of a card or inclosure in registry with the window.

Fig. 3 is a view similar to Fig. 1, showing a blank for a modified form of the invention.

Fig. 4 is a view similar to Fig. 2, showing the completed envelope made from the blank of Fig. 3.

Fig. 5 is a view similar to Figs. 2 and 4, illustrating a further modification of the envelope of 30 Figs. 1 and 2.

Fig. 6 is a view similar to Figs. 2 and 4, illustrating a modification of the envelope of Figs. 3 and 4.

Like reference characters refer to like parts in 35 the different figures.

Referring first to Fig. 1, the envelope blank therein shown provides a rectangular body portion 1, forming the front wall of the envelope and having an address-revealing window 2, here 40 shown in a substantially central location. On opposite ends of the body portion 1 project the two substantially triangular end flaps 3 and 4, the latter, in the manufacture of the envelope, being folded in on the lines 3' and 4', Fig. 1, following which a triangular bottom flap 5, having moist gum 6, 6, on its edges, is folded on the line 5' to overlap said gummed edges with the lower edges of the infolded end flaps 3 and 4, thereby to complete the back wall of the envelope.

Such an envelope, of conventional size, may be made to serve for the transmission of a card or inclosure 7 of much smaller size, (Fig. 2), with the latter held within the envelope so as to maintain registry of the sendee's name and address 50 thereon with the window or opening 2, in the

following manner:—The back flap 5 in the manufacture of the envelope receives, in suitably spaced relation to its fold line 5', the moist gum 8, the latter, upon folding in of said flap 5, adhering to the front wall 1 somewhat below the lower edge 60 of the window or opening 2; this adhesion between front and back walls constitutes a stop or barrier effective against the lower edge of the card or inclosure 7, whereby said card, notwithstanding the fact that its breadth is much less 65 than the depth of the envelope pocket, is kept vertically in a position where its upper edge coincides substantially with the line of fold 12' of seal flap 12, and where the sendee's name and address thereon is substantially at the level of 70 the window 2. However, this fixing of the vertical position of the card 7 does not take care of its lateral or endwise registry with the window 2,—the length of the card, as shown in Figs. 1, 2 and 5, being so much less than the length of 75 the envelope that the sendee's name and address thereon, by endwise or lateral movement of the card in either direction, could very easily get out of register with said window 2. According to my invention, either or both of the end flaps 3 and 80 4 of the envelope are so constructed as to cooperate with an end edge of the card 7 in preventing said card's endwise or lateral displacement within the envelope; as shown in Figs. 1, 2 and 5, the upper edges of both of the end flaps 3 and 4 are 85 so cut as to provide hooks or horns 9, 9 which, in the infolded position of said flaps, lie inwardly of and above the reentrant notches 10, 10. Said opposing notches 10, 10 in the completed envelope have their maximum spacing slightly in 90 excess of the length of the card or inclosure 7, so that when the latter is inserted, with its ends overlying the hooks or horns 9, 9, as shown in Fig. 2, the notches 10, 10 serve as stops or shoulders, effective on the end edges of said card, to 95 prevent its endwise displacement in either direction. As a means of insuring the insertion of card 7 with its ends in the desired overlying relation to the hooks or horns 9, 9, the latter, if desired, may be supplied, before the infolding of 100 flaps 3 and 4, with spots of moist gumming 11, 11, so as to adhere, when the blank is folded, to the front wall 1. But this adhesion of the hooks or horns 9, 9 is not in any way essential to the 105 operation of my invention, as the notches 10, 10 would perform their functions as stops or shoulders against endwise displacement of the inclosure 7, regardless of whether or not the horns 9, 9 are stuck down against the envelope's front wall. In the absence of such sticking down, the 110

envelope obviously is adapted to the reception, if desired, of a longer card or inclosure than the card 7; for example, a card or inclosure of substantially the full length of the envelope, or a 5 card or inclosure whose length is substantially the distance between one notch 10 and the most remote end edge of the envelope; in both cases, these longer cards would be held in registry with the window 2. As shown in Fig. 2, the upper 10 edge of the card or inclosure 7 substantially coincides with the fold line 12' of the usual sealing or closure flap 12, the latter having a band of gum 13 along its edge, adapted to be moistened and stuck down against the back wall of the completed 15 envelope following insertion of said card 7; this sealing of the envelope prevents any upward displacement of the card 7 that would affect the later's registry with the window opening 2.

In the modification of the invention shown in 20 Figs. 3 and 4, the window or opening of the front wall is offset laterally, as shown at 2', so as to lie adjacent the fold line 14' of one of the end flaps 14 of the blank; in this construction, said fold 14' serves as a limit stop, effective against 25 one end of the inclosure 7, to prevent endwise movement of the latter, and consequently the flap 14, having no function itself as a limit stop, is of substantially conventional shape and construction. The opposite end flap 15 however, according 30 to the invention, must prevent endwise displacement of the card 7 in the opposite direction, away from the fold line 14', and to this end said flap 15, substantially at the juncture of its upper and lower edges, provides the notch 16 and the adjacent hook or horn 17, for cooperation 35 with the end of card 7 in substantially the same manner as the notch 10 and hook or horn 9 of Figs. 1 and 2. In this construction, the same gumming 6 along one edge of the bottom flap 5 provides the seam between overlapped portions 40 of flaps 5 and 15, but in order to allow transmission of the envelope at a lower postal rate, the construction is such as to permit pulling out of end flap 14 for postal inspection, as shown in 45 Fig. 4, this involving the omission of the usual gumming between overlapped portions of the flaps 5 and 14. Also, for this purpose, the gumming 18 on the seal or closure flap 19 is curtailed, to avoid interference with this withdrawal of the 50 end flap 14. In this form of the invention, the registration with the window 2' of the name and address on the inclosure or card 7 is effectually maintained by making the distance between 55 notch 16 and fold line 14' substantially equal to the length of the card, thereby preventing endwise movement of the latter in either direction; movement of the card 7 up or down is prevented by the fold 19' of closure flap 19, and by the gumming 8' that unites the front and rear walls, said gumming 8' in this instance being shown as applied to the body portion 1 instead of to the flap 5.

Fig. 5 shows an envelope of the same form as 60 Figs. 1 and 2, except that it embodies the feature of permitting withdrawal of end flap 4 for postal inspection,—the gummed seam at the overlap of bottom flap 5 with the lower edge of said flap 4 being omitted, and the gumming 13' on seal flap 12 being suitably curtailed, so as to avoid sticking down of the seal flap 12 on the flap 4. In this case, with the flap 4 folded in, the notches 10, 10 in the two flaps 3 and 4 serve to fix the 70 position of the card 7, when the latter is inserted, so as to overlie the horns 9, 9 which in the present 75 case, at least as regards the horn 9 on the with-

drawable flap 4, omit any gumming that secures adhesion to the front wall 1 of the envelope.

Fig. 6 shows an envelope of the same form as 80 Figs. 3 and 4, except that it omits the feature of permitting withdrawal of end flap 14 for postal inspection. In this envelope, there is the usual gummed seam at the overlap of bottom flap 5 with the lower edge of flap 14, and the closure flap 19 has seal gumming 20 extending along substantially its entire free edge, so as to stick down, when moistened, to the flap 14 as well as to the flap 15. In this case, the hook or horn 17, adjacent the notch 16 of flap 15, is shown as stuck down, by gumming 21 against the front wall 1 of the envelope,—as distinguished from the unstuck horn 17 shown in Figs. 3 and 4. As hereinbefore pointed out, it is immaterial, so far as this invention is concerned, whether the horns or flap projections 9 and 17 of the flaps 3 and 15, respectively, be stuck down or not to the envelope's front wall, since it is the notches 10 and 16 that maintain the endwise registration of the card or inclosure 7, provided merely that the horns or projections 9 and 17 lie between said card and the front wall 1 of the envelope. 90

I claim,

1. As a new article of manufacture, an envelope having a window in one of its walls, to reveal the address on an inclosure of substantially smaller size in both dimensions than said envelope, means 105 for supporting said inclosure vertically, at the proper level for registry with said window and the free edge of the envelope's back wall providing a shoulder, in undercut relation to said free edge and spaced approximately by the length of 110 said enclosure from the opposite marginal fold of said envelope, said shoulder serving, when the enclosure is inserted in overlying relation to the undercut portion of said free edge, as a stop to hold said enclosure against substantial endwise or lat- 115 eral displacement relative to said window.

2. As a new article of manufacture, an envelope having a window in one of its walls, to reveal the address on an inclosure whose length is appreciably less than the length of the envelope pocket, 120 the free edge of the back wall of said envelope providing a pair of notches, facing each other and spaced apart by substantially the length of said inclosure, to engage the two opposite end edges of said inclosure and prevent its endwise 125 movement in either direction.

3. As a new article of manufacture, an envelope having a window in one of its walls, to reveal the address on an inclosure whose length is substantially less than the length of the envelope pocket, 130 the back wall of said envelope being constituted by a plurality of folded-in and adhesively-secured flaps, one of which on a free edge thereof provides a notch, spaced approximately by the length of said inclosure from the opposite marginal fold 135 of said envelope, said notch and said marginal fold adapted to be engaged by the opposite end edges of said inclosure and to hold the latter against endwise displacement in either direction relative to said window. 140

4. As a new article of manufacture, an envelope having a window in one of its walls, to reveal the address on an inclosure of substantially smaller size than the pocket of said envelope, 145 there being a notch in the back wall of the envelope in undercut relation to the free edge of said back wall, the material of said free edge that overhangs said notch being adhesively secured to the envelope's front wall, whereby to make said 150

- notch effective as a stop to limit the movement of said enclosure.
5. As a new article of manufacture, an envelope having a window in one of its walls, to reveal the address on an inclosure of substantially smaller size than the pocket of said envelope, there being a pair of notches in the free edge of the back wall of said envelope, said notches facing each other and spaced apart by substantially the length of said inclosure, said notches adapted to engage with the opposite end edges of said inclosure during and after the latter's insertion in said pocket to obtain and maintain the registry of said address with said window.
- 10 6. An envelope having front and back walls, the former providing a window for revealing the address on an inclosure of substantially smaller size than said envelope, and the back wall being constituted by a plurality of marginally-overlapped adhesively-joined flaps, the free edge of one of said flaps having a notch which is undercut with relation to a portion of said free edge that is adhesively joined to the envelope's front wall, thereby to prevent insertion of said enclosure in the envelope pocket except with said notch in an operative relation as a stop against an edge of said enclosure.
- 15 7. An envelope having a window in one of its walls, to reveal the address on an inclosure whose length is appreciably less than the length of the envelope pocket, the free edge of the back wall of said envelope providing a pair of notches, facing each other and spaced apart by substantially the length of said inclosure, to engage the two opposite end edges of said inclosure and prevent its endwise movement in either direction, the back wall material adjacent each notch and along said free edge being adhesively secured to the other wall of the envelope to compel said inclosure's entry between said notches.
- 20 8. An envelope having a window in one of its walls, to reveal the address on an inclosure whose length is substantially less than the length of the envelope pocket, the free edge of the back wall of said envelope providing a notch, spaced approximately by the length of said inclosure from the opposite marginal fold of said envelope, and adapted to cooperate with said marginal fold, to hold the inclosure against endwise displacement in either direction relative to said window, the back wall material in overhanging relation to said notch being adhesively secured to the other wall of the envelope, thereby to compel said inclosure, when inserted in said pocket, to make operative edgewise engagement with said notch.
